(57) **CLAIM**

The ornamental design for a knee wrap, as shown and described.

DESCRIPTION

FIG. 1 is a rear view of a knee wrap, showing our new design;

FIG. 2 is a top view thereof, the bottom view being identical;

FIG. 3 is a left side view thereof, the right side view being identical;

FIG. 4 is a front view thereof; and,

FIG. 5 is an isometric view thereof.
